DEVICE FOR CREATING LIGHT PATTERNS

Tod A. Dockstader, Westport, Conn.
(15 E. 48th St., New York, N.Y. 10017)

Filed Oct. 16, 1967, Ser. No. 9,015

Term of patent 7 years

Int. Cl. D26—02

U.S. Cl. D48—20

FIGURE 1 is a view in perspective of a device for creating light patterns, showing my new design;

FIGURE 2 is a side elevational view thereof;

FIGURE 3 is a view in perspective thereof with a cover element thereof removed;

FIGURE 4 is a bottom plan view of the cover element; and

FIGURE 5 is a side elevational view with the cover element removed.

The views of individual elements of the device in FIGURES 3-5, inclusive, are shown for purposes of disclosure.

I claim:

The ornamental design for a device for creating light patterns, substantially as shown and described.
